UNITED STATES PATENT OFFICE.

JOSEPH C. DONNELLY, OF PHILADELPHIA, PENNSYLVANIA.

MACHINE FOR MAKING WAX MATCHES.

SPECIFICATION forming part of Letters Patent No. 658,764, dated October 2, 1900.

Application filed June 9, 1893. Serial No. 477,076. (No model.)

To all whom it may concern:

Be it known that I, JOSEPH C. DONNELLY, a citizen of the United States, residing at Philadelphia, in the county of Philadelphia, and 5 in the State of Pennsylvania, have invented certain new and useful Improvements in Machines for Making Wax Matches; and I do hereby declare that the following is a full, clear, and exact description thereof, referring 10 to the accompanying drawings, in which—

Figure 1 shows a view of my machine in side elevation, lever K' and its hanger being omitted for clearness; Fig. 2, a plan view of 15 a portion of the carrier with the means for actuating it and separating the bars of its sections, the guiding-way for the carrier being partially removed; Fig. 3, a view of a section on line x x of Fig. 2 with the taper holding and guiding rolls removed; Fig. 4, a view 20 of a transverse section on line y y of Fig. 2; Fig. 5, a view of a section on line z z of Fig. 3; Fig. 6, a detail view showing in side elevation the cam and switch devices for causing 25 the moving taper-feeding clamps to remain closed during their upward movement and to open and remain open as they descend; and Fig. 7, a detail view of the feed-clamp, partly in elevation and partly in vertical section. Fig. 8 is a detail in perspective of the 30 ratchet and pawl devices and their supporting and operating parts. Fig. 9 is a detail in elevation of one of the ratchet-wheels and its pawl.

The object of my invention has been to provide 35 an improved machine for making wax matches; and to this end my invention consists in the machine and the parts thereof constructed, arranged, and combined as hereinafter specified.

It has been my special purpose in devising the present machine to provide entirely automatic means for making matches from wax taper supplied continuously from the 45 roll or coil, such taper being cut into suitable lengths by the machine and such lengths being treated to make complete matches out of them and then discharged as completed into a suitable chute or receptacle.

In the drawings, A A designate the frame 50 for supporting the various parts of the machine, such frame being of any desired con-

struction and material. Supported thereon or formed in one piece therewith are the two opposite and similar continuous guides B B, 55 each having the lower straight horizontal part, the curved portions connected with the ends of such straight part, and an upper portion, preferably, but not necessarily, straight, connecting the upper ends of the curved end 60 portions. In the inner opposing sides of these two guides are the continuous grooves or ways b b, which correspond with each other in form and direction. Their curved portions are, as shown, made wider than the 65 lower straight parts, for a purpose to be explained. Guided in these ways b b are the opposite sides of an endless carrier made up of a series of sections hinged together, so that they can as the carrier is moved along 70 pass around through the curves in the ways b b, as indicated in the drawings. This carrier, which is for the purpose of receiving and holding the butt-ends of the match-blanks while the head ends are being treated, has each 75 of its sections formed of two parallel rods C C near its opposite sides, upon which are strung a series of clamping-bars C' C', made movable to and from each other on the rods and having their ends projecting into the ways b b, 80 adapted to fit the lower straight horizontal parts of the latter. While I have shown ten of these bars in each section provided with holes c c through which the rods C C pass, I do not limit myself to such construction, 85 but can have more or less of the bars and mount them movably on the rods in any other desired way without departure from my invention. The rods C C at one end of the respective carrier-section have the shoulders 90 c' c', which engaging the outer side of the end bar limit the movement of the series of bars in that direction. The ends of the rods beyond such shoulders are pivotally connected with the adjoining ends of the rods of the next 95 carrier-section, preferably, though not necessarily, in the manner shown in the drawings. For this purpose the ends of the rods beyond shoulders c' c' are provided with holes and inserted between ears c² c² on heads c⁴ c⁴ on 100 the adjoining rods, and pins c³ c³ are passed through said ears and the rod-holes.

To force the bars of each section along the respective supporting-rods toward the shoul-

ders $c' c'$ and hold said bars pressed against each other with a yielding pressure, I provide each rod with a spring c^5 , which being between the head c^4 and the nearest or end bar 5 of the series presses at one end against the head and at the other upon the outer side of the bar. The sides of the bars which oppose each other are provided with a series of corresponding half-round grooves $c^6 c^6$ at right 10 angles to the lengths of the bars, so as to be upright as the respective carrier-section moves along or is in the horizontal part of the guideways $b b$. The size of these grooves is such that two of them will together make an opening 15 slightly smaller in diameter than the taper to be used in making the matches, so that as a piece of taper is inserted between two of the bars $C' C'$ in line with the corresponding grooves therein and the bars are brought together, as by the action of the springs $c^5 c^5$, described above, such piece will be inclosed, 20 clamped, and held in the grooves. The upper and lower ends of such grooves are enlarged or made flaring, as shown, for a purpose 25 to be described, the half-round flare of each groove end being preferably in the shape of a portion of the surface of a cone.

Each bar has the opposite sides of each of its ends beveled off, so as to form the opposite inclines $c^7 c^7$, having V-shaped spaces between the ends of adjoining bars, while on its under side as the respective carrier-section is traveling along the lower horizontal part of ways $b b$ each bar has near each of 35 its ends a downwardly-projecting tooth c^8 .

In each of the carrier-sections that bar C' which comes against the shoulders $c' c'$ on rods $C C$ has, in addition to the teeth $c^8 c^8$, two other teeth $c^9 c^9$, situated on lugs or projections extending out from the bar near its opposite ends, so as to bring said other teeth in line with each other below the space between the two adjoining carrier-sections, which is made equal to the width of one of 45 the bars.

For moving the endless carrier around through the ways $b b$ with a step-by-step motion, so as to move the bars $C' C'$ successively into position with the series of grooves $c^6 c^6$ over a given line, I provide the shaft D , journaled in suitable bearings on the frame or on arms dependent from the guides $B B$, with the two pinions $D' D'$, meshing with the series of teeth on the section-bars. This shaft is 55 also provided with two suitably-disposed ratchet-wheels $D^2 D^3$, which are actuated by pawl mechanism to impart the requisite movements to the shaft, as will be hereinafter described.

Journalled upon suitable bearings on the two uprights $E E$ of the frame, which are below the path of the carrier-sections, along the horizontal lower portions of the guides $B B$ and forward of the point where the pinions $D' D'$ mesh with the teeth on the bars $C' C'$, is the driving-shaft F , which is shown as provided with a band or belt wheel F' , to be driven by

suitable connections from any suitable motor or source of power.

An upright plate G , parallel to the bars $C' C'$ of the endless carrier, is at its sides guided in vertical guideways $e e$ on the inner sides of the uprights $E E$, so as to be movable to and from the carrier in a direction at right angles to the travel of the same. In 75 one vertical face of this plate there are upright half-round grooves $g g$, corresponding in number and relative position with the grooves $c^6 c^6$ in the carrier-bars. For a purpose to be explained hereinafter while the 80 lower portions of these plate-grooves are made of the same size as those in the bars the upper portions are made larger, so as to just accommodate a half-segment of the taper to be used. A transverse slot g' through 85 the plate at the point where the different-sized portions of the grooves meet extends across the series of grooves and stops just short of the plate sides. A second plate G' , parallel to the other, is connected therewith 90 by pins $g^2 g^2$ on such other plate engaging holes $g^3 g^3$ in plate G' . This second plate G' is provided with grooves g , exactly like those in the other, with their lower portions made smaller than the upper ones, so that when the 95 two plates are pressed together a taper placed between them in line with corresponding opposing grooves therein will be clamped and held by the lower parts of the grooves and simply inclosed and guided without being 100 clamped by the upper groove parts. Upon the outer side of plate G' are the two ears $g^4 g^4$, to which is pivotally attached, by means of pin g^5 , the upper end of connecting-rod G^2 , the lower end of which is sleeved on the 105 crank F^2 on the shaft F . With this construction and the plates G and G' connected together, as shown and described, by the pins on the former engaging the holes in the latter plate as the shaft F is revolved to cause 110 the crank to actuate the connecting-rod the two plates will be reciprocated up and down toward and from the under side of the endless carrier. The position of the guide for plate G is such that as the carrier comes 115 to a rest after each step-by-step movement there will be a series of grooves in the section-bars directly over and in line with the grooves in the plates $G G'$, as indicated in the drawings. (See Figs. 1 and 3.) For holding the plate G' close against the other as it moves upward and then moving it away therefrom as it moves downward and holding it so removed throughout the downward travel I provide said plate on its opposite 125 edges with the guide-rollers $g^6 g^6$, situated at or near the top and bottom of the plate, respectively. Upon the inner sides of the uprights $E E$ are the grooves $e' e'$, in position to be engaged by said rollers. Of these 130 grooves the former is a straight vertical one parallel to groove or way e , which guides plate G , and near enough thereto to cause the plate G' to be held close against the other plate as

the rollers $g^6 g^6$ ride up grooves $e' e'$ during the raising of both plates by the connecting-rod G^2 . The grooves e^2 , of which there are two on each upright E , have their upper and lower ends running into groove e' , while their main portions between such ends are substantially parallel with such groove.

Near the upper end of each groove e^2 , which is made inclined toward groove e' , there is a spring-actuated switch e^3 , which is pressed by its spring e^4 to cause it to stand normally in an inclined position across the groove e' , so as to guide a roller g^6 , which may have traveled above it and be descending, over into the groove e^2 in the manner indicated in Fig. 6. As a roller g^6 nears the upper end of its travel up groove e' it engages the switch and swings it over out of its way, so that it forms a continuation of the outer guiding-wall of such groove and keeps pressed toward plate G to continue the taper-clamping action of the two plates during their continued upward movement. As the roller passes off of the upper end of the switch, so that the latter is swung over across groove e' by its spring, the side wall of the latter is engaged by the roller, so that the plates $G G'$ are still held forced together until the downward movement of such plates begins, when the rollers on opposite sides of plate G' engage the respective switches and are cammed thereby over into the grooves $e^2 e^2$ to cause unclamping of the tapers by the plate-grooves.

Attached to the uprights $E E$, below and in line with plate G , is the stationary bar H , having grooves $h h$ in line with and of the same size as the lower portions of those in said plate. A similarly-grooved movable clamping-bar H' is guided in its movements to and from bar H by pins $h' h'$ on the uprights passing through holes $h^2 h^2$ in the bar, near its opposite ends, while springs $h^3 h^3$ on such pins, confined by nuts $h^4 h^4$, press the bar over toward bar H to cause any tapers passed up through the bar-grooves to be clamped and held in the latter.

To move bar H' against the stress of springs $h^3 h^3$, so as to cause the tapers to be unclamped, I provide the opposite ends of said bar with the rollers $h^5 h^5$ and place upon shaft H^2 , journaled in suitable bearings on uprights $E E$, the two cam-wheels $h^6 h^6$, each having a depressed portion to allow the bar to remain pressed against bar H during the downward travel of the clamping-plates $G G'$ away from the endless carrier and the raised part h^7 to engage the respective roller h^5 and force it over to move and hold the bar H' away from bar H while the clamping-plates are moving up again toward the carrier.

Upon the outer ends of shaft H^2 , which is to be driven from shaft F by a belt H^3 , running over suitable pulleys $H^4 H^5$ on the respective shafts, as shown, or by other connections, as desired, are fixed the crank-disks $h^8 h^8$, carrying the wrist-pins $h^9 h^9$, each engaging a longitudinal slot k in one of the le-

vers $K K'$, pivoted upon arms $k' k'$, attached to the guide-frames $B B$. The wrist-pins, being similarly situated upon the crank-disks, will actuate the two levers in the same direction and at the same time. Lever K is at its farther end provided with the pawl k^2 , which has its upper end adapted to engage the teeth of the ratchet-wheel D^2 on shaft D , hereinbefore described, and turn such wheel and shaft forward as the pawl-carrying end of the lever descends. A spring k^3 holds the pawl to its work, while a stop-arm k^4 on the lever limits the pawl's motion under stress of the spring. The other lever K' has its outer end connected by link k^5 with the swinging arm k^6 , pivoted on shaft D , close to ratchet-wheel D^3 , with its one tooth. Pivoted to the outer end of this arm is the pawl k^7 , held pressed against the periphery of said ratchet-wheel by spring k^8 and having its outer end adapted to engage the one tooth on such wheel when it is brought around into its reach by rotation of the shaft D , so as to turn both wheel and shaft forward a distance dependent upon the travel of the pawl. Lever K is pivoted so that its pawl can move ratchet-wheel D^2 one tooth or far enough to make the endless carrier travel through the space occupied by one of its clamping-bars C' , while lever K' is so pivoted that pawl k^7 has three times the travel of pawl k^2 , so that when it engages the tooth on ratchet-wheel D^3 it will turn the latter and the shaft to move the carrier through a space equal to the width of three of its bars. The single tooth on this ratchet-wheel is so situated that it comes around within the reach of pawl k^7 each time that the last bar of a carrier-section is brought by the motion of the latter to place its wax-taper-receiving grooves $c^6 c^6$ in line with those on the reciprocating clamping-plate G . As the pawl k^7 is actuated by its moving lever, it will then, by turning the ratchet-wheel and shaft D three times as far as the pawl k^2 turns the latter for each movement of its actuating-lever, move the endless carrier along through the space of three bars, as is necessary to carry the space between two carrier-sections past the plane of the upward travel of the grooved face of clamping-plate G' when the latter is held against plate G and bring the grooved face of the first bar of the succeeding carrier-section up to such plane.

If desired to prevent backward movement of ratchet-wheel D^2 and shaft D , I provide the stop-pawl k^9 , pivoted to the frame and engaging the teeth of said wheel, as shown in Fig. 1.

The motion of the crank-disks $h^8 h^8$ is so timed with reference to the described means for actuating the clamping-plates $G G'$ and the clamping-bar H that the pawls are caused to move the respective ratchet-wheels in the manner described after clamping-plates $G G'$ have traveled downward so as to approach the lower limit of their travel and during a short portion of their upward movement.

The rolls $L L$ of taper, of which there is

one for each one of the series of clamping-grooves, are placed upon a shaft L' , which is supported in open bearings L^2 and is provided with a brake-pulley L^3 , over which passes the friction brake-strap L^4 , with a weight L^5 attached to one end to regulate the amount of friction resisting the turning of the shaft. The rollers can, if desired, be connected with the shaft frictionally, so as to be capable of rotating thereon under stress of an extra pull on the tapers, or they could be simply journaled on a stationary spindle and be each provided with a friction brake-pulley and weighted brake-strap, like such features

15 just described as used with the rotary shaft. From the rolls the lines of tapers $M M$ are led around the grooved guide-wheels L^6 , journaled on spindle L^7 and thence up into and through the respective clamping-grooves in 20 the bars H and H' . From there they run up into the corresponding grooves in the plates $G G'$. In line with the slot g' , when the clamping-plates are at the uppermost limit of their travel toward the endless carrier, is the horizontal knife-blade N , which at its opposite ends is guided in the horizontal guideways n in arms on the uprights $E E$, so as to be movable into and from said slot when the latter is brought up opposite it by the movement 30 of the clamping-plates. The cutting edge, which is carried by the inward movement of the cutter across the series of grooves in the plates $G G'$, so as to cut through all the tapers held by the latter, is preferably made inclined a little to a line at right angles to the cutter's movement, so as to secure an easy drawing cut. From the outer ends of the cutter arms $n' n'$ extend outward through 35 slots in the supporting-frame. They are provided with openings in line with the travel of the cutter-engaging pins $n^2 n^2$, on which are springs $n^3 n^3$, which engaging the cutter-arms force the same, and consequently the cutter, normally away from the path of the clamping- 40 plates $G G'$. On the rear or back of the cutter are journaled antifriction-rollers $n^4 n^4$, which are in the paths of the single teeth or lugs n^5 , similarly situated on the two disks $n^6 n^6$, fixed on the shaft n^7 , driven from shaft 45 H^2 by belt-and-pulley connection, as shown. The shaft n^7 is so timed that these lugs engage the respective rollers $n^4 n^4$ on the cutter and force the latter over to make it cut quickly just as the crank F^2 on the shaft F 50 comes to and is passing its upper dead-center. Having been thus moved and released by the lugs, the cutter is quickly retracted by its springs $n^3 n^3$.

For forcing the spring-pressed bars $C' C'$ of 55 a carrier-section apart to allow the upper ends of the tapers held and moved upward by the clamping-plates $G G'$ to be inserted easily between them in position to be clamped in the corresponding and opposite bar-grooves when 60 the bars are brought together again I provide on opposite sides of the carrier the reciprocating wedge-blocks $O O$, supported in guides

60 on the frame and having their inner wedge-shaped ends adapted to be forced into the V -shaped spaces between the outer ends of adjoining bars $C' C'$, made broad enough to slightly separate the bars, as shown in Fig. 2. 70 Each of these wedge-blocks has a retracting-spring o' to draw it back from its bar-separating position and an antifriction-roller o^5 in 75 position to be engaged and forced inward toward the carrier by a cam o^3 on a rotary disk o^4 . There is one of these cam-disks for each wedge-block fixed on a shaft o^5 , journaled in a bearing on the frame and having attached 80 to it a pulley o^6 , driven by a belt o^7 from a wheel o^8 on shaft H^2 .

The hereinbefore-described pinions for moving the endless carrier by meshing with the teeth on the bars of the carrier-sections 85 are situated to the rear of the point where the wedge-blocks operate upon the bars, a distance greater than the length of one of the carrier-sections, so that the pinions cannot engage the teeth on the bars of a section 90 which is passing and being operated upon by the wedge-blocks, but will mesh with those on the next section to the rear of that one. To the rear of such pinions and above the endless carrier is a transverse bar P , vertically reciprocating in guides $P' P'$, engaging 95 its ends. On its under side such bar is provided with a series of pins $p p$, corresponding in number and relative situation with and adapted to enter the taper-clamping 100 holes made up of the corresponding opposing grooves in the abutting faces of adjoining carrier-section bars $C' C'$. The situation of this bar P over the horizontal or straight traveling part of the carrier is such that 105 each time that the carrier comes to a rest after being moved a step in the manner and by the means hereinbefore described the division-line between the bars $C' C'$, and consequently a row of taper-holding openings, 110 will be directly below the pins $p p$, so that as the bar P descends the latter will enter such openings and push out therefrom the ends of the pieces of taper held therein.

For actuating the bar to cause it to descend each time that the carrier comes to a rest I use the shaft P^2 , journaled in bearings on the portions $B B$ of the frame of the machine and having the cranks $p' p'$, connected by links $p^2 p^2$ with the top of the bar. Such 120 shaft can be driven by a belt P^3 , passing over pulleys P^4 and P^5 on the shafts n^7 and P^2 , respectively.

Underneath the carrier in position to receive the matches discharged therefrom by 125 the pins $p p$ is the inclined guide or chute P^6 to guide the matches to any desired receptacle.

Upon a suitable standard R just forward of the clamps G and G' is the trough or receptacle R' , holding the igniting composition 130 to form the heads of the matches and provided with the rollers $R^2 R^2$ to carry the composition from the body in the receptacle up

into the path of the lower ends of the match-blanks or short pieces of taper which have been cut off from the rolls and are carried onward by the clamping-bars of the moving carrier. The shaft R^3 , on which these rollers are fixed, is revolved by a belt R^4 , running over a pulley R^5 thereon, and one, R^6 , fixed on the shaft H^2 . One or more rotary stirrers R^7 for stirring up the contents of the trough or receptacle can be driven also from shaft H^2 by suitable belt-and-pulley connections.

The operation of my machine, which may be quite fully understood from the foregoing description and drawings, is briefly as follows: With the lines of taper fed from the spools up through the grooves of the clamping-bars H H' and clamping-plates G G' so as to project above the tops of the latter and said plates raised to insert such ends of the tapers between two of the carrier-section bars C' C' , which are held apart by the wedge-blocks provided for that purpose, the clamping-plates G G' are held together to grasp the tapers in the lower narrower portions of their grooves g g , and the clamping-bar H' is held away from bar H by the cams engaging the rollers on the ends of the former bar. The cams which have forced and are holding the wedge-blocks in between the ends of bars C' C' then pass off of the rollers on the wedge-blocks, and the retracting-springs quickly retract the latter to disengage them from the bars. By the action of the springs c^5 c^5 on rods C C the separated bars C' C' are quickly brought together to clamp the ends of the tapers between them. In the meantime the cutter is forced in through the slot in plate G , so as to cut through the tapers just above the points where they are clamped in the smaller portions of grooves g g in plates G G' . As the motion of the machine continues the clamping-plates begin to descend and the clamping-bar H' is released by the cams, which have been holding it away from bar H , so that it is forced quickly by springs h^3 h^3 inward toward the latter bar to clamp the tapers in the bar-grooves. The part of the descent of the plates G G' causes the guide-rollers on the latter plate to ride out over the switches toward and into grooves e^2 e^2 , so that such plate is moved away from plate G to unclamp the tapers between them. As the tops of these clamping-plates come below the ends of the cut-off pieces of taper forming match-blanks, which are now held by their upper ends in the grooves of two abutting carrier-section bars C' C' , the pawl-actuating levers are, through their pin-and-slot connections with the disks or wheels on shaft H^2 , moved in a direction to cause their respective ratchet-wheels on the carrier-driving pinion-shaft to turn forward. If the single tooth on the ratchet-wheel D^3 is not within the reach of its engaging pawl k^7 , the latter merely moves without performing any work, while the other pawl moves its ratchet-wheel one tooth, or just

far enough to carry a carrier-section bar C' past the line of upward movement of the tapers by the described feeding-clamp and bring the grooved upright face on the rear side of such bar into position, so that its said grooves will be in line with the tapers to be inserted in them. When the last bar of a section has been reached and a series of match-blanks have been inserted in the grooves in the forward face of it and the rear face of the abutting bar, the single tooth on the ratchet-wheel D^3 is by the rotation of the shaft D necessary to move the carrier to bring the division-lines between the bars of a section successively over the taper-feeding clamps brought into reach of the pawl k^7 , which, because of the extra motion of its actuating-lever, then turns the wheel D^3 , and consequently the shaft D , far enough to carry the opening between the section just operated upon and the adjoining one past the taper feeding and inserting devices, and bring the division-line between the last and next to the last bars of the succeeding section over such devices. The carrier having been moved to bring a new row of taper-holding openings made up of grooves in the abutting faces of the section-bars into position above the tapers, and the rollers on clamping-plate G' having moved from grooves e^2 e^2 into straight groove e' , such plate clamps the tapers again in its grooves and those of plate G , and both plates move upward again. In the meantime the bar H' is by the cam devices provided therefor moved away from bar H , so as to leave the tapers free to be drawn upward by clamping-plates G G' . The wedge-blocks being again driven inward by their actuating-cams separate the new pair of bars C' C' , so that the ends of the tapers projecting above the clamping-plates G G' are inserted between them in line with their grooves c^6 c^6 . The operation just above described is then repeated, the result being that as the carrier-sections are moved along they have their rows of taper-receiving openings successively filled with match-blanks, which they carry on over the composition-applying device, which puts on their lower ends the desired heads of igniting material. After being thus headed the pieces of taper travel around with the carrier-sections as the latter pass along ways b b , so that the applied heads have opportunity to cool and harden before reaching the discharging device, which, as shown, consists of the bar P with its pins p p to enter the taper-holding openings formed of the grooves in the section-bars c' c' and push the contained butt-ends of the completed matches out therefrom. The flaring ends of these openings made by enlarging the ends of the half-round grooves in the bars C' C' facilitate the entry of the pins p p of the discharger and prevent any possibility of the tapers being inserted in place catching or striking upon the lower edge of a bar C' in such way as to hinder the passage of the ta-

per ends. With the lower parts only of the corresponding grooves in plates G G' made small enough to grasp the tapers and the upper parts larger, so as to simply inclose and 5 guide without grasping the latter, the pieces of taper forming the match-blanks, which are cut off by the knife, will not be in danger of being pulled down and out from between the clamping-carrier section-bars as the plates 10 G G' descend to take a new hold of the tapers farther down.

Obviously the machine can be readily adapted to operate upon any desired number of tapers simultaneously. It will as supplied with 15 the tapers or lines of material from which the match-blanks are to be made and with the composition-applying device kept supplied with the required igniting material carry on the manufacture and discharging of completed matches continuously and entirely automatically. With a number of tapers acted upon simultaneously, as in the machine shown and described, the matches can be turned out very rapidly, while the heads are by the travel 20 of the endless carrier before the discharging device is reached given plenty of time to cool and harden.

Having thus described my invention, what I claim is—

30 1. In an automatic power-driven machine for making wax matches, the combination with a main driving mechanism, of a progressively-movable carrier, operative connections between said mechanism and carrier, a reciprocating taper-feeding device arranged to thrust the taper toward, and operating automatically in respect to, the carrier, and having provisions for clamping the taper during the advance stroke of the device, and for 40 holding straight and in line during its insertion in the carrier substantially all that portion of the taper which is next to be severed, means for releasing the taper-clamp during the retraction of said device, a cutter constructed and arranged to sever the taper when 45 it has been introduced to the carrier, and means for operating the cutter at predetermined intervals, substantially as described.

2. In an automatic power-driven machine 50 for making wax matches, the combination with a main driving mechanism, of a progressively-movable carrier, operative connections between said mechanism and carrier, a reciprocating taper-feeding device arranged 55 to thrust the taper toward, and operating automatically in respect to, the carrier, and having provisions for clamping the taper during the advance stroke of the device and for holding straight and in line during its insertion 60 in the carrier substantially all that portion of the taper which is next to be severed, means for releasing the taper-clamp during the retraction of said device, a knife reciprocative independently of the feeding device 65 in a plane intersecting the taper, a support and guide for the knife, and means connected with and operated from the main driving

mechanism for reciprocating the cutter at predetermined intervals, substantially as described.

3. In an automatic power-driven machine for making wax matches, the combination, with a main driving mechanism, of a progressively-movable carrier, operative connections between said mechanism and carrier, a reciprocating taper-feeding device arranged to thrust the taper toward the carrier, said device including a section movable at right angles to the feeding movement so as to clamp or release the interposed taper, and having provision for holding straight and in line during its insertion in the carrier substantially all that portion of the taper which is next to be severed, means connected with and operated from the main driving mechanism for advancing 85 said device to the carrier while the latter is at rest and for retracting the device while the carrier is moving onward, and means for automatically effecting the clamping and the unclamping of the taper preparatory to the 90 advancement and the retraction of the feeding device, respectively, together with a cutter constructed and arranged to sever the taper into match-lengths, and means for operating said cutter at predetermined intervals, 95 substantially as described.

4. In an automatic power-driven machine for making wax matches, the combination, with a main driving mechanism, of a progressively-movable carrier, operative connections 100 between said mechanism and carrier, a reciprocating taper clamping and feeding device, means for advancing said device to the carrier while the latter is at rest and for retracting the device while the carrier is moving onward, and means for effecting the clamping and the unclamping of the tapers preparatory to the advancement and the retraction of the feeding device, respectively, together with a supplementary clamping device to act upon 110 the tapers during the retraction of the feeding device, a cutter constructed and arranged to sever the tapers into match-lengths, and means for operating said cutter at predetermined intervals, substantially as described. 115

5. In an automatic power-driven machine for making wax matches, the combination, with a main driving mechanism, of a progressively-movable carrier, operative connections between said mechanism and carrier, a reciprocating taper-feeding device having a 120 lower clamp and an upper guiding portion through which the tapers freely extend, means for operating and releasing the clamp at predetermined intervals, a knife or cutter, 125 and means for operating it in a manner to sever the tapers when they have been introduced to the carrier, substantially as described.

6. In a machine for making wax matches, 130 the combination, with a main driving mechanism, a progressively-movable carrier, operative connections between said mechanism and carrier, of a bodily-reciprocatve clamp

and feed device for lines of taper, said device comprising a portion in which the tapers are clamped, and a series of guides through which the tapers freely extend, and an independent cutter movable transversely of the tapers thus clamped, and means connected with and actuated from the main driving mechanism for automatically operating the cutter, substantially as described.

10 7. In combination with the carrier, consisting of a series of sections hinged together, each section being provided with means for holding match-blanks or the like, means for moving such carrier with a step-by-step motion 15 to carry the carrier-sections past a given point, which consists in two ratchet-toothed pieces moving together and connected with the carrier so as to move the same, the one having a series of ratchet-teeth, and the other 20 a single tooth, in combination with two pawls, one for each ratchet-toothed piece, and means for actuating such pawls, arranged to move the pawl for the single-toothed ratchet-piece a greater distance than the other pawl travels, substantially as and for the purpose specified.

25 8. In combination with a carrier consisting of a series of connected sections, each containing a series of clamping-bars, a rotary 30 shaft, connections between the same and the carrier whereby the latter is moved, the two ratchet-wheels on such shaft, one having only one tooth, and the other a series of teeth, a pawl to engage the teeth of the second wheel 35 actuated to move the latter a distance to carry the carrier through a space equal to the width of one clamping-bar, and a pawl to engage the single tooth on the other wheel, actuated to move the same far enough to carry the 40 carrier through a space equal to the width of two clamping-bars, and the space between two adjoining carrier-sections, substantially as and for the purpose described.

45 9. In combination with a series of connected carrier-sections, each having a series of clamping-bars, the teeth on such bars, the teeth on projecting portions of each end bar below the space between such bar and the first one of the next section, the rotary shaft, the pinions 50 thereon to mesh with said teeth, the ratchet-wheel on the shaft having a series of ratchet-teeth, the second ratchet-wheel also fixed on the shaft, and having one tooth, separate pawls for the two ratchet-wheels, the pawl- 55 actuating levers, and means for moving such levers, adapted to give the lever connected with the pawl for the one-toothed wheel, a throw sufficient to turn the shaft a greater distance than the other pawl turns it, so as to 60 move the carrier a distance equal to the width of two clamping-bars and the space between the two carrier-sections, substantially as and for the purpose specified.

65 10. In combination with a source of supply of the taper, or other material, in a continuous strip, the stationary clamp through which the strip is passed, one or more springs to hold

such clamp closed, the cam for opening it, the reciprocating clamp consisting of the two plates moving together, to and from the stationary 70 clamp, a guide to guide one of such plates in a straight line toward and from the stationary clamp, and guiding devices to hold the other plate against the first plate as it moves from the stationary clamp, and separating it 75 therefrom during its travel in the opposite direction, such guiding devices guiding the parts of the movable clamp in their feeding as well as in their clamping movement, substantially as and for the purpose set forth. 80

11. The reciprocating feed-clamp, consisting of the two plates connected by the pins on one engaging holes in the other, the straight guideways guiding one of the plates, guide-rollers on the sides of the other plate, a straight 85 guideway for such rollers, the two camways running at their opposite ends into such straight guideways, and the switches near the upper ends of the camways to shift the rollers on the plate over into the camways as they 90 descend, substantially as and for the purpose described.

12. In a match-machine, the combination, with a progressively-moving carrier, and its supporting and operating parts, of two opposing 95 clamping and feeding plates connected to each other so as to reciprocate together to and from said carrier, but be capable of being separated and brought together again during reciprocation, a guiding device for one of the 100 plates, guide-rollers at the sides of the other plate, a straight guideway for such rollers, and the two camways running at their upper and lower ends into the straight guideway, the switches at the points where the upper 105 ends of the camways run into the straight guideway, and springs holding such switches normally swung across the straight guideway, substantially as and for the purposes specified.

13. In a match-machine, the combination, with a progressively-moving carrier, and its supporting and operating parts, of a reciprocating clamp and feed device, to clamp the lines of taper and feed them progressively to the carrier, said device being provided with 110 a slot immediately above the clamping portion, a cutter reciprocative independently of the clamp and feed device, and means for forcing the cutter in through the slot to cut the clamped tapers, substantially as described. 115

14. In combination with means for holding and supplying a strip of material from which matches are to be made, and a suitable carrier to receive and hold portions cut off from such strip, a reciprocating clamp grooved to hold and guide the strip and adapted to surround the same up to a point close to its end, means for moving such clamp toward and from the carrier into which the strip is to be thrust, means for opening and closing the 125 clamp as it moves away from and toward the carrier, respectively, and a cutter arranged to cut the strip at a point below the upper edge of the strip-surrounding part of the 130

clamp, and means for actuating such cutter, substantially as and for the purpose specified.

15. The feeding-clamp for feeding a taper, consisting of the two separable plates, having 5 corresponding taper-receiving grooves in their opposing faces, with their lower portions made small enough to grasp the taper when the plates are forced together, and their upper portions made larger to simply surround 10 and guide the taper, in combination with a cutter to cut the taper above the smaller portions of the receiving-grooves of the clamp, substantially as and for the purpose set forth.

16. The feeding-clamp for feeding lines of 15 taper, which consists of the two separable plates having the series of corresponding taper-receiving grooves in their opposing faces, with their lower portions made small enough to grasp the tapers when the plates 20 are forced together and their upper portions made larger, and a way for a cutting-blade to pass across the upper ends of the lower portions of the grooves, in combination with a cutter, and means for forcing the same 25 through such way and retracting it, substantially as and for the purpose described.

17. In combination with a series of rolls or other sources of supply of taper, a movable carrier, and its supporting and operating 30 parts, said carrier having the transverse bars with a series of corresponding grooves in their abutting faces, corresponding in number with the tapers to be operated upon, the reciprocating feed-clamp having its clamping- 35 plates provided with grooves on their oppos-

ing faces through which the taper passes, situated similarly to those in the carrier-bars, means for moving such clamp toward and from the carrier, and cutting mechanism operating in a fixed path independently of the 40 clamp to act on the tapers at a point below the carrier, substantially as and for the purpose shown.

18. In combination with sources of supply of several lines of taper, the grooved stationary clamp, means for opening and closing said clamp, the correspondingly-grooved reciprocating feed-clamp, means for opening and closing it as it moves toward and from the stationary clamp, respectively, a carrier 50 moving progressively across the path of the feed-clamp provided with a series of spring-pressed clamping-bars, with their opposing faces having taper-receiving grooves corresponding in number and position with those 55 on the feed-clamp, springs to press such bars together, means for separating them to allow the passage of taper ends between them by the reciprocating feed-clamp, and then releasing them, and a cutter operating in a fixed 60 path independently of the clamp to cut the tapers off below the carrier, substantially as and for the purpose set forth.

In testimony that I claim the foregoing I have hereunto set my hand this 25th day of 65 May, 1893.

JOSEPH C. DONNELLY.
